UNITED STATES PATENT OFFICE

JOSEPH BECKER, OF PITTSBURGH, PENNSYLVANIA, ASSIGNOR, BY MESNE ASSIGNMENTS,
TO THE KOPPERS COMPANY OF DELAWARE, A CORPORATION OF DELAWARE

COKING RETORT OVEN

Application filed September 29, 1926. Serial No. 138,414.

My invention relates to coke ovens and it has particular relation to means for, and methods of, charging coke ovens.

My invention has, for one of its objects, to provide a coke oven having a plurality of charging openings that is so arranged that all smoke and gases evolved during the charging operation may be withdrawn through two offtake openings.

10 A second object of my invention is to provide a method of charging coke ovens having a plurality of charging openings in such manner that the passage of gases to the one or the other end of the oven will not be prevented during the charging operation.

A further object of my invention is to provide a coke oven having charging means therefor so constructed and arranged that the passage of gases through the oven is not blocked at more than one point during charging whereby the number of offtake openings may be substantially independent of the number of charging openings.

A still further object of my invention is to provide a larry car having hoppers of different capacities whereby the oven is filled to the top at not more than one point during the charging operation.

It has been previously proposed to provide coke ovens with a plurality of charging openings and to provide an offtake opening at each side of the charging openings in order to effect the removal of any smoke and gases that may be entrapped when the oven is filled to the top by the discharge of coal from the corresponding hoppers. Such provision has been advisable by reason of the fact that the entrapped gases are under considerable pressure and will, if allowed to escape, pollute the surrounding atmosphere to a degree that is highly objectionable.

In accordance with the present invention, I provide a coke oven having a single offtake opening at each end of the oven. The oven is provided with hoppers that correspond in number with the charging openings. Only one of the hoppers is of such capacity that the coal contained therein is sufficient to fill the oven completely at its charging opening. Accordingly, all of the

smoke and gases evolved during charging may be withdrawn through the one or the other offtake opening and the necessity for additional offtake openings is, therefore, avoided.

55 In the accompanying drawings:

Figure 1 is a view, partially in longitudinal section and partially in elevation, of a coke oven and its associated apparatus embodying my invention; and

60 Fig. 2 is a view, similar to Fig. 1, of a modification.

Referring particularly to Fig. 1, a coke oven 1 comprises a coking chamber 2 having a top 3 that is provided with charging openings 4 and 5. The top 3 is provided with offtake openings 6 and 7 that are located adjacent to the respective ends of the coke oven. The offtake openings 6 and 7 are respectively connected by ascension pipes 8 and 9 to collecting mains 10 and 11 that extend along the ends of the ovens in the usual battery.

Each of the ascension pipes is provided, at its upper portion, with a valve 13 and an operating handle 14 therefor whereby the 75 ascension pipe may be opened to the atmosphere in case, for example, it is desired to remove carbon or other deposits therefrom. Each of the ascension pipes is further provided with a steam jet 15 that is suitably controlled by a valve 16 for a purpose to be later described. Each of the collecting mains is connected to a pipe 17 through which the smoke and gases withdrawn from the coke oven 1, as well as other coke ovens in the battery, 80 are conducted to the usual by-product house.

85 The top 3, which is a portion of the continuous top of the battery, supports rails 19, upon which a larry car 20 operates. The larry car 20, which is not shown in all of its 90 details, comprises, in general, a frame 21 that is provided with wheels 22 for co-operating with the rails 19.

The frame 21 supports a relatively small hopper 23 and a relatively large hopper 24 95 that are arranged to supply the coking chamber 2 through the corresponding openings 4 and 5. Each of the hoppers is provided with a sleeve 25 that is slidable upon the discharge portion of the hopper. The sleeves 25 may be 100

manipulated by any suitable and usual apparatus (not shown).

It may be assumed that the battery of ovens, of which the oven 1 is a part, is in 5 operation and that the several ovens are in various stages of the coking operation. The collecting mains 10 and 11 are operated under suitably regulated pressure, above atmospheric pressure, of the gases that are evolved 10 during the coking operation. This pressure condition is essential by reason of the necessity for preventing the passage of highly heated air from the usual cross regenerators beneath the floors of coke ovens which might 15 cause serious damage to the silica brick of the oven because of the combustion induced by the presence of such air.

It may be assumed further that the coke 20 has been pushed from the oven 1 and that it is being recharged in accordance with the usual practice. The larry car 20, with the hoppers 23 and 24 filled with the proper amounts of coal, is brought to such position 25 that the sleeves 25 register with the charging openings 4 and 5.

Before, or simultaneously with, the discharge of coal into the coking chamber 2, the valves 16 of the steam jets 15 are opened to increase locally the pressure differential in 30 the ascension pipes that is exerted against the mains 10 and 11. The steam jet, which is directed outwardly from the oven, exerts an injector action whereby the smoke and gases evolved during the charging operation are 35 drawn outwardly at a relatively high rate.

The lids or covers 27, only one of which is shown, are removed from the charging openings and the sleeves 25 are lowered into engagement with the oven top in order to prevent 40 coal spillage around the charging hole. The hopper 23 is then discharged through the charging opening 4 and the coal therefrom fills the oven substantially to the extent indicated in the left-hand portion of the oven. 45 It will be noted, however, that the peak of the pile of coal in the oven does not reach the top thereof and that, accordingly, the free passage of gases through the oven is not blocked. The sleeve 25 of the hopper 23 may 50 then be lifted and the lid 27 placed in position, as is illustrated in the drawings, without escape of smoke.

The contents of hopper 24 are either next, or simultaneously with, the contents of hopper 55 23, discharged into the oven, the method of charging always resulting in leaving an open gas space below the charging opening 4, under the hopper 23, whereby approximately three-fourths of the gases evolved pass 60 under the charging opening 4 to the main 10, while only about one-fourth pass into main 11. It is general practice, in charging coke ovens with a plurality of charging openings, to discharge the outside hoppers first 65 and then the intermediate hoppers, in order

to have the least amount of smoke discharge into the atmosphere and in the case illustrated herein showing only two charging openings, the proportions of coal in the hoppers are so arranged that, regardless of the order in which they are discharged, there will always be free gas space through which the gases may pass into the collecting mains. 70

In order to completely distribute the contents of the hopper 24 into the oven, the usual leveling apparatus, comprising a leveling bar 28, only a portion of which is shown, operates through the leveling door 29 to level the coal in the oven in the usual and generally adopted manner. The charging lids are, of course, replaced as soon as all 75 coal has discharged into the oven.

The leveling operation will continue until the upper surface of the coal is substantially level. As soon as the coal beneath the charging opening 5 is leveled, the gases may be removed through either of the openings 6 and 7. The steam jets 15, which are adjusted in accordance with the quantity of gases evolved in the oven, are left in operation only during 80 the short period while the oven is being charged. Their use is not necessary during the normal operation of the oven after charging, since the pressure exerted by the gases within the oven is sufficient to effect their removal against the pressure above atmospheric pressure in the collecting mains. 85 90 95

It will be understood that the operation described above will be repeated in connection with the other ovens of the battery as 100 they are charged successively in accordance with the charging schedule.

Reference may now be had to Fig. 2, in which the construction and operation differ only slightly from those of the apparatus of Fig. 1. Similar numerals are employed to designate corresponding parts in both views. The oven 30 is provided with three charging openings 31, 32 and 33, with which co-operate 105 hoppers 34, 35 and 36. It will be noted that the hopper 35 is relatively large, while the hoppers 34 and 36 are relatively small. 110

The end hoppers are discharged and the corresponding lids 27 placed over the openings prior to the discharge of the hopper 35. 115 Thereafter, the levelling operation proceeds as in the oven of Fig. 1, the conditions in the two arrangements being substantially identical in these respects.

It will be appreciated that I have provided 120 a coke oven having a plurality of charging openings and charging means co-operating therewith so constructed and arranged that the oven is eventually completely charged without any gas escaping in the atmosphere. The oven is never divided into more than two compartments in which gases are evolved, whereby only two offtake openings are necessary to remove the smoke and gases. 125

While I have shown, by way of example, 130

ovens with two and three charging openings respectively, it will be further appreciated that, if the oven be filled to the top at one point only during the charging operation,

5 only two offtake openings are necessary, regardless of the number of charging openings.

My improved method of charging is of particular advantage in that it may be adapted to existing installations wherein larry 10 cars are provided with hoppers of equal capacities by regulating the amount of coal supplied to the several hoppers whereby only one of the hoppers contains sufficient coal to complete the oven charge. Accordingly, 15 my invention is not limited to the use of larry cars having hoppers of unequal capacities.

The foregoing and other advantages will be apparent to those skilled in the art to which my invention appertains. It is obvious 20 that many modifications will occur to those skilled in the art of constructing and operating coke ovens and it is desired, therefore, that my invention be not limited except as set forth in the appended claims.

25 I claim as my invention:

1. The combination with a horizontal coke oven having a plurality of charging openings in the top thereof and spaced from each other longitudinally of the oven; of a plurality of 30 coal charging containers for cooperating with the charging openings respectively to charge said oven, the aggregate coal capacity of all of said containers approximately equaling the total capacity required for charging 35 the oven with coal up to a substantially level surface throughout the length of the oven adjacent the top thereof so as to leave a gas space above the charge from one end to the 40 other of said oven, and one of said containers being of substantially greater coal capacity than the coal capacity of any container of the remainder of said containers; and gas off-take openings communicating with said 45 oven at the top thereof on opposite sides of the charging opening for the container of greater coal capacity.

2. The combination with a horizontal coke oven having two coal charging openings in 50 the top thereof and spaced from each other longitudinally of the oven; of two coal charging containers for cooperating with the two charging openings respectively to charge the oven, the aggregate coal capacity of both of 55 said containers approximately equaling the total capacity required for charging the oven with coal up to a substantially level surface throughout the length of the oven adjacent the top thereof so as to leave a gas space above 60 the charge from one end to the other of said oven, and one of said containers being of substantially greater coal capacity than the coal capacity of the other; and gas off-take openings communicating with said oven at the top 65 thereof on opposite sides of the charging

opening for the container of greater capacity.

In testimony whereof, I have hereunto subscribed my name this 28th day of September, 1926.
